UNITED STATES PATENT OFFICE.

CARL G. PRITCHARD, OF WARREN, OHIO, ASSIGNOR TO THE HARRIS AUTOMATIC PRESS COMPANY, OF CLEVELAND, OHIO, A CORPORATION OF OHIO.

AUTOMATIC SCRAPER CONTROL FOR ROTOGRAVURE-PRINTING PRESSES.

1,362,633.

Specification of Letters Patent. Patented Dec. 21, 1920.

Application filed May 29, 1917. Serial No. 171,613.

To all whom it may concern:

Be it known that I, CARL G. PRITCHARD, a citizen of the United States, and a resident of Warren, in the county of Trumbull and State of Ohio, have invented certain new and useful Improvements in Automatic Scraper Control for Rotogravure-Printing Presses, of which the following is a specification, reference being made to the accompanying drawings, forming a part thereof.

My invention relates to rotogravure or intaglio printing-presses, and the invention is embodied in improved mechanism for automatically controlling the scraper knife, used to remove the surplus ink from the etched plate on the form cylinder simultaneously with the stoppage of the printing operation, either by throwing off the impression, or by disconnecting the press as a whole from the driving source of power. In printing-presses of this type the printing operation is performed by a copper plate or shell suitably secured to the form cylinder, the outer surface of which is etched or engraved, such etched or engraved portions being adapted to contain the ink, while the smooth portions of the plate are free from ink. The ink is fed to the form cylinder in relatively large quantities from the ink fountain, and a sharp scraper knife is arranged tangentially to the circular etched plate and used to remove all surplus ink from the outermost surfaces of the plate. The edge of the knife is also arranged parallel to the axis of rotation of the form cylinder and the surplus ink falls back into the fountain as the cylinder is rotated. In presses of this type, it is necessary to employ devices to lift the scraper knife from the surface of the copper plate upon the stoppage of the printing operation, lest the sharp edge of the knife cut into and ruin the etched surface of the copper plate by any reverse movement of the press, thereby rendering the plate useless for further printing.

The objects of my invention are, among other things, to provide a simple and effective automatic scraper control mechanism, which may be actuated simultaneously either with the throwing-off of the impression or with the stoppage of the press, controlled either by the operator or automatically by a sheet detector device and tripping mechanism which operate upon

the failure of the feed of a sheet to the press.

I attain this result by the mechanism shown in the accompanying drawings in which—

Figure 1 is a side elevation of my improved control showing so much of a rotary press as is necessary to illustrate my invention;

Fig. 2 is a plan view of a part of the press shown in Fig. 1;

Fig. 3 is an end view partly in cross-section, of the tripping mechanism shown in Figs. 1 and 2.

Fig. 4 is a side elevation of a modified form of my invention the same being shown in connection with the clutch throw-off of the press;

Fig. 5 is a plan view, similar to Fig. 2, only taken of the modified form of my invention shown in Fig. 4; and

Fig. 6 is an end view, partly in cross-section of the tripping mechanism shown in Figs. 4 and 5.

Similar numerals referred to similar parts throughout the several figures.

Referring more particularly to the embodiment of my invention shown in Figs. 1, 2 and 3, the frame 7 supports the bearings for the plate cylinder 8, carrying the etched copper plate 9, and the impression cylinder 10, said cylinders being mounted on the shafts 11 and 12, respectively. The cylinders 8 and 10 are so constructed and arranged in the frame 7 as to form a printing couple. The plate and impression cylinders have each fastened thereto suitable gears whose pitch-diameter coincides with the periphery of the respective cylinders. These gears intermesh and form the driving mechanism to secure the proper rotation for the cylinders. The power is derived from the belt 13 passing around the pulley 14 on the shaft 15 journaled in the frame 7; the shaft 15 carries the pinion 16 which intermeshes with the pinion 17 mounted on the shaft 12. Since these are common forms of printing-press construction and are well-known in the art, they are not shown in detail in the drawings.

The shaft 11 carrying the plate cylinder 8 is mounted at both ends in the eccentric bearings 18, one of which has the arm 19 projecting on the outside of the frame 7 as shown more particularly in Figs. 1 and 2.

The toggle levers 20 and 21 connect the outer end of the arm 19 to the frame 7, the lever 20 being journaled to the outer end of the arm 19, while the lever 21 is 5 pivoted to the frame at 22. Connected to the outer end of the lever 21 is the link 23 the other end of which is pivoted to the arm 24 mounted on the oscillating shaft 25 which is actuated by the coil spring 26 secured about the shaft 25 as shown in Fig. 2. The hand-lever 27 is secured to the collar 28 mounted on the shaft 25 to restore the impression, or to manually operate the impression throw-off and scraper control. 10 The shaft 25 is held in the position shown in Fig. 1 by the latch 29 secured to the rock-shaft 30 journaled in the bracket 31 in the frame 7, which latch 29 engages a notch 32 in the sleeve 33 mounted on the shaft 25 as 15 shown in detail in Fig. 2.

Secured to the frame 7 is the horizontal ink fountain vat 34 to contain the ink to be applied to the plate 9 by the inking roll 35 as this roll is rotated by being in contact with 20 the outer surface of the plate. Mounted on the rock-shaft 36 which is journaled in the frame 7 is the hub 37 of the scraper knife 38 which preferably is removably secured to the hub 37 by set screws (not shown). The 25 edge of the knife 38 normally bears on the outer surface of the plate 9, as shown in Figs. 1 and 2, through the action of the gravity weight 39 secured to the outer end of the arm 40 mounted on the sleeve 41 affixed 30 to the rock-shaft 36 outside the frame 7 as shown in Fig. 2. The sleeve 41 has also secured thereto, outside the frame 7, the projecting arm 42 which carries on its outer end the pivoted rod 43. This rod 43 extends 35 rearwardly, as shown, and has mounted on its under side near its outer end the lug 44 adapted to engage and coact with the lug 45 secured to the sleeve 33, when the parts are in the position shown in Fig. 1. When the 40 rod 43 is shifted toward the left, either through the lifting of the hand-lever 27 or through the counter-clock-wise rotation of the shaft 25 by the release of the latch 29, the edge of the scraper knife 38 is removed 45 from contact with the outer surfaces of the plate 9, and simultaneously therewith the toggle levers 20 and 21 will be broken in the direction of the arrow shown in Fig. 1 through the movement of the link 23 to 50 throw off the impression.

Preferably this latch 29 would be released automatically through trip mechanism on the feeder, as shown more particularly in Fig. 3. In Figs. 1, 2 and 3, 46 designates 55 the feed table, and in Fig. 3, 47 indicates the sheet of stock that is being fed to the press. Extending transversely above the feed table 46 and journaled to projections in the frame 7 is the shaft 48 which carries the 60 arm 49 connected by the rod 50 pivoted to

the pin 51 on the impression cylinder shaft 12, so as to impart to the shaft 48 an oscillating movement during the operation of the press. 52, 52 designate two grooved collars rigidly secured to the shaft 48 and adjacent 70 each grooved collar 52 is the disk 53 of substantially the same diameter as the collars 52, which disk is affixed to the inner end of the tubular shaft 54 which is loosely sleeved on, and incloses a portion of the shaft 48, as 75 shown in Fig. 3. The shaft 54 carries the arm 55 the outer end of which bears against the arm 56 mounted on the block 57 affixed to the rock-shaft 30. 58 indicates the trip-lever pivoted at 59 between the parallel sides 80 of the grooved collars 52, so that its larger and heavier arm is held from falling into the opening 60 cut in the top of the feed-table 46 by the interposition of the stock 47, as 85 shown in Figs. 1 and 3. At the opposite end 85 the trip-lever 58 is T-shaped to form the tooth 61, and in the peripheries of the sides of the collars 52 and also in the periphery of the disk 53, are formed cut-outs 62 and 63 respectively. Ordinarily the tooth 61 rests 90 against, or is in proximity to, the periphery of the disk 53; it can engage with the cut-out 62 of the collars 52 only when it can fall into the cut-out 63 of the disk 53. When 95 this occurs, the disk 53 and its shaft 54, which are normally at rest, are locked to and turn with the oscillating shaft 48. The entrance of this tooth 61 into locking engagement with the disk 53 will occur upon the failure or interruption in the feed supply. 100 Where the stock 47 is in proper position, as shown in Figs. 1 and 3, the curved longer arm of the trip-lever 58 will engage therewith and will be supported thereby so as to be prevented from lowering into the opening 105 60, and from turning sufficiently to interlock with the disk 53. If the stock 47 should, at any time, be interrupted or absent, the longer arm of the trip-lever 58 will fall of its own weight into the opening 60, thereby 110 causing the tooth 61 to interlock with the cut-out 63 in the disk 53. Thus the tubular shaft 54 will be caused to oscillate with the shaft 48 so as to cause the arm 55 to lift the arm 56 to release the latch 29 engaging the 115 notch 32 in the sleeve 33 on the shaft 25. Through the movement of this herein-described mechanism, the spring-impelled shaft 25 is partially rotated in a counter-clock-wise direction to swing the eccentric bearings 120 18 to throw off the impression by separating the plate cylinder 8 from the impression cylinder 10, and at the same time lift the edge of the scraper knife 38 from the outer surface of the plate 9, all controlled by the 125 stock.

It is also apparent that the operator, by moving the hand-lever 27 to the left in Fig. 1 and lifting the latch 29 may simultaneously throw off the impression and lift the 130

scraper knife 38 from the plate 9 by a single movement so that the two throwing-off operations work together and in unison. In practice, it is essential that the scraper knife 38 be restored to its contact position with the plate 9 on the cylinder 8 at least a half revolution of the cylinder 8 in advance of the restoration of the printing relation of the cylinders 8 and 10, so that the outer surface 10 of the plate 9 may be cleaned of surplus ink before beginning to contact with the sheet 47 on the impression cylinder 10. This is readily accomplished by raising the rod 43 until the lug 44 clears the lug 45 secured to the sleeve 33, which will permit the scraper knife 38 to contact with the plate 9 through the action of the gravity weights 39.

In the modified form of my invention shown in Figs. 4, 5 and 6, I have embodied 20 same in a construction in which the scraper throw-off is connected to one of the clutch members secured to the driving shaft, so that the scraper knife is thrown off the plate cylinder with the disconnecting of the power 25 clutch upon the stoppage of the press. When the clutch members are reset upon the starting of the press, the edge of the scraper knife is restored to contact with the plate cylinder, or the knife may be placed 30 in operative position on the cylinder before the press is started.

Referring to Figs. 4 and 5, 64 designates the frame of the press in which the form cylinder 65 carrying the etched plate 66, 25 and the impression cylinder 67 are mounted on the shafts 68 and 69 respectively journaled in the frame 64, the two cylinders 65 and 67 forming a printing couple. The two cylinders are geared together as has been 40 hereinbefore described with reference to the cylinders 8 and 10. Power is transmitted to the impression cylinder 67, from the loose and fixed pulleys 70 and 71 to the driving shaft 72 journaled in the frame 64 as shown. 45 73 is the positive clutch member slidably secured to the shaft 72 and is adapted to engage the clutch member 74 mounted on the shaft 75; the clutch 74 carries the miter-gear 76 which engages with the miter-gear 50 77 mounted on the impression cylinder shaft 69 to secure the counter-clock-wise rotation of the impression cylinder 67. 78 is a stub-shaft secured to the frame 64 and 79 is a sleeve journaled on the shaft 78 which 55 sleeve 79 has a depending arm 80 carrying at its lower end the clutch yoke 81 adapted to engage, and coact with, the annular groove 82 formed in the clutch member 73 as shown in Fig. 4. Extending upwardly from the 60 sleeve 79 is the arm 83 having the rod 84 pivotally secured to its outer end.

The rod 84 extends forwardly of the press and near its outer end carries the lug 85 on its under side adapted to engage and coact 65 with the pin 86 secured to the outer end of

arm 87 mounted on the transverse shaft 88 journaled in the frame 64. The shaft 88 carries the hub 89 upon which the scraper knife 90 is removably secured in the same manner as the knife 38. 91 is the ink fountain from which ink is supplied to the plate 66 through the rotatable ink roller 92. The shaft 88 carries the arm 93 from which the gravity weights 94 are suspended to normally maintain the edge of the knife 90 in 70 contact with the plate 66. When the rod 84 is moved to the left either by the lifting of the hand-lever 95 or by the action of the automatic sheet-detector device hereafter to be described, the knife 90 will be thrown off 80 from the plate 66 simultaneously with the disconnecting of the clutch members 73 and 74 which stops the press. Preferably the two throw-offs will be controlled and actuated by the automatic sheet-detector device, 85 shown more particularly in Fig. 6.

In Figs. 4, 5 and 6, 96 indicates the feed-table, and in Fig. 6, 97 designates the sheet of stock that is being fed to the press. Extending transversely above the feed-table 90 96 and journaled to projections in the frame 64 is the rock-shaft 98 which carries the arm 99 connected by the rod 100 which is pivoted to the pin 101 in the impression cylinder shaft 69, so as to impart to the shaft 98 an 95 oscillating movement during the operation of the press. 102, 102 designate two grooved collars rigidly secured to the shaft 98, and adjacent each grooved collar 102 is the disk 103 of substantially the same diameter as the collars 102, which disk 103 is secured to the inner end of the tubular shaft 104, which is loosely sleeved on, and incloses a portion of, the shaft 98, as shown in Fig. 6. The shaft 104 has rigidly secured to its 100 outer end the collar 105 upon which is mounted the arm 106 which, in turn, is connected to the hand-lever 95 by the link 107. 108 designates the trip-lever pivoted at 109 between the parallel sides of the grooved 110 collars 102 so that its longer and heavier arm is held from falling into the opening 110 cut in the top of the feed-table 96 by the interposition of the stock 97 as shown in Figs. 4 and 6. At the opposite end the trip- 115 lever 108 is T-shaped to form the tooth 111, and in the peripheries of the sides of the collars 102, and also in the periphery of the disk 103 are formed cut-outs 112 and 113 respectively. Ordinarily the tooth 111 rests 120 against, or is in proximity to, the periphery of the disk 103; it can engage with the cut-out 112 of the collars 102 only when it can fall into the cut-out 113 of the disk 103. When this occurs the disk 103 with its shaft 125 104, which are normally at rest, are locked to and turn with the oscillating shaft 98. The entrance of this tooth 111 into locking engagement with the disk 103 will occur upon the failure or interruption in the feed 130

supply. When the stock 97 is in proper position, as shown in Figs. 4 and 6, the curved longer arm of the trip-lever 108 will engage therewith and will be supported thereby, so as to be prevented from lowering into the opening 110, and from turning sufficiently to interlock with the disk 103. If the stock 97 should, at any time, be interrupted or absent, the longer arm of the trip-lever 108 will fall of its own weight into the opening 110, thereby causing the tooth 111 to interlock with the cut-out 113 in the disk 103. Thus the tubular shaft 104 will be caused to oscillate with the shaft 98 so as to cause the arm 106 to lift the hand-lever 95 through the link 107 to simultaneously disconnect the clutch members 73 and 74 on the one hand, and to throw the scraper knife 90 off the surface of the plate 66 on the other. When the clutch is reset the knife 90 is automatically brought at once into contact with the plate 66 as soon as the press starts, or the knife may be returned to the cylinder before starting by raising the rod 84 out of engagement with the pin 86.

The foregoing constructions both embody the principles of my invention as applied to a two-cylinder press, but it is obvious that my invention is applicable to other forms of printing-presses, and that other combinations and modes of operation may be made, the foregoing being sufficient to disclose the underlying principles and advantages involved.

35 I claim as my invention:

1. In a printing-press having a plurality of coöperating printing members, inking devices for one of said members, means for removing surplus ink from said last-mentioned member, means for tripping said printing members, and means directly actuated by said tripping means for placing said ink-removing means in inoperative position simultaneously with the stoppage of the printing operation, said last means allowing the ink-removing means to be moved into operative position before the printing relation of said printing members is resumed.
- 40 2. In a printing-press having a plurality of coöperating printing members, inking devices for one of said members, means for removing surplus ink from said last-mentioned member, means for tripping said printing members, and automatic means directly actuated by said tripping means for placing said ink-removing means in inoperative position simultaneously with the stoppage of the printing operation, said last means allowing the ink-removing means to be moved into operative position before the printing relation of said printing members is resumed.
- 45 3. In a printing-press having a plurality of coöperating printing members, inking devices for one of said members, means for removing surplus ink from said last-mentioned member, means for tripping said printing members, and automatic means directly actuated by said tripping means for placing said ink-removing means in inoperative position simultaneously with the stoppage of the printing operation, said last means allowing the ink-removing means to be moved into operative position before the printing relation of said printing members is resumed.
- 50 4. In a printing-press having a plurality of coöperating printing members, inking devices for one of said members, means for removing surplus ink from said last-mentioned member, means for tripping said printing members, and automatic means directly actuated by said tripping means for placing said ink-removing means in inoperative position simultaneously with the stoppage of the printing operation, said last means allowing the ink-removing means to be moved into operative position before the printing relation of said printing members is resumed.
- 55 5. In a printing-press having a plurality of coöperating printing members, inking devices for one of said members, means for removing surplus ink from said last-mentioned member, means for tripping said printing members, and automatic means directly actuated by said tripping means for placing said ink-removing means in inoperative position simultaneously with the stoppage of the printing operation, said last means allowing the ink-removing means to be moved into operative position before the printing relation of said printing members is resumed.
- 60 6. In a printing-press having a plurality of coöperating printing members, inking devices for one of said members, means for removing surplus ink from said last-mentioned member, means for tripping said printing members, and automatic means directly actuated by said tripping means for placing said ink-removing means in inoperative position simultaneously with the stoppage of the printing operation, said last means allowing the ink-removing means to be moved into operative position before the printing relation of said printing members is resumed.
- 65 7. In a printing-press having two impression members to form a printing couple, inking devices for one of said members, means contacting with said last-mentioned member to remove surplus ink, means for throwing off the impression, means directly actuated by said throw-off means for breaking such contact simultaneously with the impression throw-off, and means for restoring such contact before the impression is thrown on.
8. In a printing-press having two impression members to form a printing couple, inking devices for one of said members, means contacting with said last-mentioned member to remove surplus ink, means for throwing off the impression, means directly actuated by said throw-off means for breaking such contact simultaneously with the impression throw-off, and means for restoring such contact before the impression is thrown on.

devices for one of said members, means for removing surplus ink from said last-mentioned member, means for tripping said printing members, and automatic means directly actuated by said tripping means and controlled by the stock, for placing said ink-removing means in inoperative position simultaneously with the stoppage of the printing operation, said last means allowing the ink-removing means to be moved into operative position before the printing relation of said printing members is resumed.

4. In a printing-press having a plurality of coöperating printing members, inking devices for one of said members, means for removing surplus ink from said last-mentioned member, means for tripping said printing members, means directly actuated by said tripping means for placing said ink-removing means in inoperative position when the impression is thrown off, and means for restoring said ink-removing means into operative position before the impression is thrown on.

5. In a printing-press having a plurality of coöperating printing members, inking devices for one of said members, means for removing surplus ink from said last-mentioned member, means for tripping said printing members, automatic means directly actuated by said tripping means for placing said ink-removing means in inoperative position when the impression is thrown off, and means for restoring said ink-removing means into operative position before the impression is thrown on.

6. In a printing-press having a plurality of coöperating printing members, inking devices for one of said members, means for removing surplus ink from said last-mentioned member, means for tripping said printing members, automatic means directly actuated by said tripping means and controlled by the stock, for placing said ink-removing means in inoperative position when the impression is thrown off, and means for restoring said ink-removing means into operative position before the impression is thrown on.

7. In a printing-press having two impression members to form a printing couple, inking devices for one of said members, means contacting with said last-mentioned member to remove surplus ink, means for throwing off the impression, means directly actuated by said throw-off means for breaking such contact simultaneously with the impression throw-off, and means for restoring such contact before the impression is thrown on.

8. In a printing-press having two impression members to form a printing couple, inking devices for one of said members, means contacting with said last-mentioned member to remove surplus ink, means for throwing off the impression, means directly actuated by said throw-off means for breaking such contact simultaneously with the impression throw-off, and means for restoring such contact before the impression is thrown on.

- member to remove surplus ink, means for throwing off the impression, automatic means directly actuated by said throw-off means for breaking such contact simultaneously with the impression throw-off, and means for restoring such contact before the impression is thrown on.
9. In a printing-press having two impression members to form a printing couple, inking devices for one of said members, means contacting with said last-mentioned member to remove surplus ink, means for throwing off the impression, automatic means directly actuated by said throw-off means and controlled by the stock, for breaking such contact simultaneously with the impression throw-off, and means for restoring such contact before the impression is thrown on.
10. In a printing-press having printing and impression members combined with means for separating said members at will, a scraper normally contacting with the surface of said printing member, means directly actuated by said member-separating means for raising said scraper from said surface when said printing and impression members are separated, and means for allowing said scraper to lower to said surface before the printing relation of said members is restored.
11. In a printing-press having printing and impression members combined with automatic means for separating said members, a scraper normally contacting with the surface of said printing member, means directly actuated by said member-separating means for raising said scraper from said surface when said printing and impression members are separated, and means for allowing said scraper to lower to said surface before the printing relation of said members is restored.
12. In a printing-press having printing and impression members combined with automatic means, controlled by the stock, for separating said members, a scraper normally contacting with the surface of said printing member, means directly actuated by said member, separating means for raising said scraper from said surface when said printing and impression members are separated, and means for allowing said scraper to lower to said surface before the printing relation of said members is restored.
13. In a printing-press having printing and impression members combined with means for separating said members, a scraper normally contacting with the surface of said printing member, means directly and simultaneously actuated by said member separating means for raising said scraper out of contact with said printing-
- member surface, and means for allowing said scraper to lower into contact with said surface before the printing relation of said members is restored.
14. In a printing-press having printing and impression members combined with automatic means for separating said members, a scraper normally contacting with the surface of said printing member, means directly and simultaneously actuated by said member separating means for raising said scraper out of contact with said printing-member surface, and means for allowing said scraper to lower into contact with said surface before the printing relation of said members is restored.
15. In a printing-press having printing and impression members combined with automatic means, controlled by the stock, for separating said members, a scraper normally contacting with the surface of said printing member, means directly and simultaneously actuated by said member separating means for raising said scraper out of contact with said printing-member surface, and means for allowing said scraper to lower into contact with said surface before the printing relation of said members is restored.
16. In a printing-press having a plurality of coöperating printing members, inking devices for one of said members, means for removing surplus ink from said last-mentioned member, means for tripping said printing members, means directly actuated by said tripping means for placing said ink-removing means in inoperative position simultaneously with the stoppage of the printing operation, automatic devices for operating said last means, and devices under the control of the operator for also operating said means, said devices allowing said ink-removing means to be moved into operative position before the printing relation of said members is restored.
17. In a printing-press having a plurality of coöperating printing members, inking devices for one of said members, means for removing surplus ink from said last-mentioned member, means for tripping said printing members, means directly actuated by said tripping means for placing said ink-removing means in inoperative position simultaneously with the stoppage of the printing operation, automatic devices, controlled by the stock, for operating said last means, and devices under the control of the operator for also operating said means, said devices allowing said ink-removing means to be moved into operative position before the printing relation of said members is restored.

CARL G. PRITCHARD.
